WALL CONSTRUCTION

Frederick M. Small, York, Pa., assignor to
 Martin-Parry Corporation, York, Pa., a corporation of Delaware

Application April 8, 1939, Serial No. 266,891

6 Claims. (Cl. 189—34)

This invention relates to a wall construction for buildings and more particularly to the structure of studs and the like for forming partitions.

An object of the invention is to provide a wall construction particularly suitable for non-bearing partitions so that such partitions can be expeditiously installed or removed.

Another object of the invention is to provide a wall supporting member such as a stud or furring strip which can be installed, without employing the usual fastening means such as screws or nails, to secure a wall supporting structure to the interior surfaces of a room.

A further object of the invention is to provide a wall supporting member, such as a stud or furring strip, which is mounted in compression between the ceiling and floor of a room so as to be secured therein.

A further object of the invention resides in the provision of a stud or furring strip which can be installed without the usual fastening devices and to which wall panels may be easily attached for forming the interior surface of the room.

A still further object of the invention is to provide a wall supporting member such as a stud or furring strip with adjustable structure for placing the member in compression between the floor and ceiling of a room so as to retain the member in place.

Other objects and advantages of the invention will appear in the following description of the preferred embodiment of the invention shown in the attached drawings of which:

Figure 1 is a vertical section of the lower portion of a wall stud taken on line 1—1 of Fig. 2;

Figure 2 is a horizontal section of the stud taken on the line 2—2 of Fig. 1 and showing panels attached thereto;

Figure 3 is a side elevation of the lower portion of a stud in accordance with the present invention showing panels attached thereto;

Figure 4 is a front elevation of a furring strip embodying the present invention;

Figure 5 is a horizontal section taken on line 5—5 of Fig. 4;

Figure 6 is a side elevation of the stud shown in Fig. 4;

Figure 7 is a view in elevation of a locking plate;

Figure 8 is a side elevation of the plate of Fig. 7, and

Figure 9 is a view in elevation of a combined locking plate and panel supporting member.

Referring more particularly to the drawings, the stud structure shown in Figs. 1 to 3 includes

the stud body 10, a stud guiding and bearing plate member shown generally at 11, an expansion member or jack 12, and a locking plate 13. A preferred form of stud is formed of thin sheet metal and has the cross section shown in Fig. 2. It will be noted that the stud body is provided with channels 14 on all four sides thereof and that these channels have portions 15 of the stud body partly closing the channel to retain the expansion member 12 or panel clip plates 16 as will be hereinafter described. The bottom portions 17 of the channels 14 are provided with depressions 18 to receive projections 19 upon the locking plate 13 and as will be later described the cooperating depressions 17 and projections 18 enable the initial position of the expansion member 12 to be varied so as to properly position the expansion member.

The stud guiding and bearing plate 11 includes a bottom plate 19 to which is secured, as by welding or otherwise, an upstanding sleeve member 20 which is inserted within the stud body 10. The sleeve 20 contacts all four interior surfaces of the stud so as to prevent horizontal shifting of the stud relative to the bearing plate 19 in any direction. As shown in Figs. 1 and 2 the depressions 17 in the bottom of the channels 14 result in projections 21 on the interior of the stud body and these projections bear against the sleeve 20.

It is apparent that, if other means are employed to secure the expansion member 12 and the panels to the stud, these depressions 17 and the resulting projections 21 may be eliminated and the sleeve allowed to contact directly with the interior surfaces of the stud. The bearing plate 19 is provided with an upstanding annular member 22 adjacent one side of the sleeve 20 upon which is mounted a bushing 23 to slidably receive a threaded portion 24 forming a part of the expansion member 12. A nut 25 screw threaded upon the threaded portion 24 bears upon the bushing 23 so that rotation of the nut 25 raises or lowers the expansion member 12. As shown in Fig. 3 the upper end of the expansion member 12 is formed into a plate-like member 26 which is of greater lateral dimension than the opening of the channel 14 so as to be retained in the channel by the overlying portions 15 of the stud. The plate-like portion 26 is of less thickness than the depth of the channel 14 throughout the major portion of its area and has a shoulder 27 provided upon the interior surface thereof for engaging the lower portion of the locking plate 13.

The expansion member 12 is secured to the stud by first inserting the locking plate 13. The

plate 13 is of less lateral dimension than the opening in the channel 14 as shown in Fig. 2 and may be inserted through the opening in the channel so that the projections 18 thereupon register with the depressions 17 in the bottom of the channel. The depressions 17 and the projections 18 are so arranged that the locking plate 13 may be shifted laterally as well as vertically and in the specific embodiment shown the locking plate 13 may have three lateral positions. Thus the projections 18 may register with the columns of depressions 17, which are indicated at A, in one position or may be shifted laterally to register with the columns of depressions indicated at B or those indicated at C. The depressions of the columns B are slightly above those in A and those of C are slightly above those of B so that lateral shifting of the locking plate 13 also shifts the plate vertically by a slight increment. By this structure small vertical adjustments of the plate 13 can be made. After the plate 13 has been placed in the desired position the flat portion of the expansion member 12 is slipped upwardly within the channel 14 from the bottom end of the stud until the shoulder 27 abuts against the lower edge of the plate 13. The upper portion 26 of the expansion member 12 cooperates with the locking plate 13 to hold the projections of the latter within the depressions 17 and thus the expansion member 12 is locked against vertical movement relative to the stud.

Preferably the bearing plate 19 rests upon a fibrous cushion member 28 positioned upon the floor of the room and the upper end of the stud is preferably provided with a suitable bearing plate and cushioning member (not shown) positioned against the ceiling of the room. By turning the nut 25 the stud may be placed in compression between the ceiling and floor of the room to retain the stud fixedly in position. Spacing members 29 preferably extend between the adjacent studs of a wall and interlock with the bearing plate 19 as shown at 30. A similar structure may be employed for the ceiling of the room so that the studs are uniformly and correctly spaced for the reception of panels or other wall structures. If desired the bearing plates 19 and spacing members 29 may be secured to the floor by screws or other fastening means extending through the aligned apertures 31 and 32 in the bearing plate and spacing members respectively.

As shown in Fig. 2, the channels 14 may be employed in the securing of panels 33. The locking plate 13 is positioned in a channel 14 in exactly the same manner as described for the attachment of the expansion member 12. A clip plate 16 provided with panel attaching lugs 34 and clip plate positioning lugs 35 is then positioned in the channel to hold the projections 18 of the locking plate 13 in the depressions 17. Such a clip plate 16 is shown in Fig. 3 above the expansion member 12 and it will be noted that the diagonal dimension of the clip plate is less than the width of the opening of the channel 14 so that the clip plate may be inserted through this opening and then turned approximately 45° in either direction to lock the same behind the portions 15 of the stud body overlying the channel. The panels 33 may be formed with channels 36 to resiliently receive the lugs 34 in order to attach the panels to the stud.

As shown in Figs. 3 and 9 a locking plate 37 similar to the locking plate 13 may be employed to give the panels 33 vertical support. The lock-

ing plate 37 is provided with a horizontal extending portion 38 positioned below the lower end of the panel 33 to support the same. Also the locking plate 37 may be provided with an intermediate lug 39 for supporting the panel clip plate 16 in which event the lugs 35 of the clip plate shown in Fig. 2 may be omitted.

An expansion structure similar to that shown in Figs. 1 to 3 may be employed to secure a furring strip 40 shown in Figs. 4, 5 and 6 against a wall 41. Such furring strips 40 are held in compression between the floor and ceiling of a room in exactly the same manner as the studs hereinbefore described. A preferred furring strip may be made of thin sheet metal rolled into a configuration similar to that shown in cross section in Fig. 5. It will be noted that the furring strip is provided with a channel 14 provided with depressions 17. The channel 14 receives a locking plate 13 having projections 18 and an expansion member 12 in the same manner as the channel 14 of the stud 10. A bearing plate 42 provided with an upstanding annular portion 22 to receive a bushing 23 forms the base support of the furring strip and preferably rests upon a cushioning member 43. A suitable bearing plate and cushioning member (not shown) may also be provided for the upper end of the furring strip and rotation of the nut 25 places the furring strip in compression between the ceiling and floor of the room. In many cases it has been found desirable to bow or deform the furring strip 40 so that the middle portion thereof is pressed tightly against the wall 41 when the ends of the furring strip are held adjacent the wall on the floor and ceiling. The channel 14 of the furring strip is also employed for attaching panels or other wall surfacing material in the same manner as the channels 14 of the stud 10 shown in Figs. 1 to 3.

The present invention provides either a stud or furring strip which may be formed of thin sheet metal and which may be installed in a building without breaking the surface of the floor, ceiling or wall finishes and without the usual fastening means such as screws or nails.

The cross sectional configuration of either the stud or furring strip provides for extremely high mechanical strength even though very thin sheet metal is employed and the overall dimensions of the members in the horizontal plane are likewise very small. The studs or furring strips provide for easily attaching panels or other surface structure thereto and also for supporting the lower edges of such panel structures in the case of uneven floors. It is apparent that molding members (not shown) may be employed to conceal the joint between the panel structure and the floors and that these moldings may be secured to the bearing plates at the ends of the studs or furring strips so that a complete room finishing structure may be carried by the studs and furring strips.

The invention is particularly useful for refinishing the walls of rooms and for installing partitions such as those used in subdividing office buildings, but may also be used for new construction. The structures described do not destroy the existing finishing surfaces of rooms in which they are installed. They are easily and quickly installed and removed, and partitions formed thereby can be readily moved.

While I have disclosed the preferred embodiments of my invention it is understood that the invention is not to be limited to the details

thereof but may be varied within the scope of the following claims.

I claim:

1. A building frame element adapted to be mounted between spaced supports said element comprising an elongated frame member provided with an undercut channel along at least one side thereof, a bearing member for one end of said frame member and relatively movable longitudinally of said frame member, an expansion member for moving said bearing member having a portion insertable within said channel, and means for securing said expansion member against longitudinal movement in said channel, said means comprising depressions in the bottom of said channel and a locking plate having projections registering with said depressions.

2. A building frame element adapted to be mounted between spaced supports, said element comprising an elongated frame member provided with an undercut channel along at least one side thereof, a bearing member for one end of said frame member and relatively movable longitudinally of said frame member, an expansion member for moving said bearing member having a portion insertable within said channel, and means for securing said expansion member against longitudinal movement in said channel including a locking plate engaging said insertable portion and said channel, depressions provided on one of said locking plate or channel and interfitting projections provided on the other.

3. A building frame element for supporting panels forming a wall and adapted to be mounted between spaced supports, said frame element comprising a frame member having channels extending longitudinally of the sides thereof and a bearing member for one end of said frame member and relatively movable longitudinally of said frame member, panel attaching means adjustably secured in at least one of said channels, and means adjustably secured in one of said channels for causing relative movement between the bearing member and the frame member whereby to increase the length of said frame element.

4. A building frame element for supporting panels forming a wall and adapted to be mounted

between spaced supports, said frame element comprising a frame member having channels extending longitudinally of the sides thereof and a bearing member for one end of said frame member and relatively movable longitudinally of said frame member, panel attaching means adjustably secured in at least one of said channels, and an expansion member having a portion insertable within one of said channels for causing relative movement between the bearing member and the frame member whereby to increase the length of said frame element.

5. A building frame element for supporting panels forming a wall and adapted to be mounted between spaced supports, said frame element comprising a frame member having channels extending longitudinally of the sides thereof and a bearing member for one end of said frame member and relatively movable longitudinally of said frame member, panel attaching means adjustably secured in at least one of said channels, an expansion member having a portion insertable within one of said channels for causing relative movement between the bearing member and the frame member whereby to increase the length of said frame element, said expansion member including a locking member in engagement with said insertable portion and with said last mentioned channel for securing the expansion member against longitudinal movement in the channel.

6. A building frame element for supporting panels forming a wall and adapted to be mounted between spaced supports, said frame element comprising a frame member having channels extending longitudinally of the sides thereof and a bearing member for one end of said frame member and relatively movable longitudinally of said frame member, panel attaching means adjustably secured in at least one of said channels, and expansion means disposed exteriorly of said frame member and having a portion adjustably secured in another of said channels for causing relative movement between the bearing member and the frame member whereby to increase the length of said frame element.

FREDERICK M. SMALL.
